UNITED STATES PATENT OFFICE

2,532,264

TANK TYPE VACUUM CLEANER

Archie E. Smith, Stratford, Conn., assignor to
 General Electric Company, a corporation of
 New York

Application October 22, 1947, Serial No. 781,455

5 Claims. (Cl. 183—37)

1

My invention relates to vacuum cleaners and more particularly to vacuum cleaners of the tank type.

It is an object of my invention to provide a vacuum cleaner of the tank type including an improved arrangement of the various elements of the cleaner in a compact unit.

It is another object of my invention to provide a vacuum cleaner of the tank type including a cord reel.

It is a further object of my invention to provide a vacuum cleaner of the tank type incorporating a cord reel and including an improved arrangement for maintaining the cord in any desired position.

It is still another object of my invention to provide a vacuum cleaner of the tank type including an improved arrangement for removably latching a cover in position.

Further objects and advantages of my invention will become apparent as the following description proceeds and the features of novelty which characterize my invention will be pointed out with particularity in the claims annexed to and forming part of this specification.

For a better understanding of my invention reference may be had to the accompanying drawings in which Fig. 1 is a perspective view of a vacuum cleaner incorporating my invention; Fig. 2 is an exploded perspective view partly broken away showing details of the vacuum cleaner illustrated in Fig. 1; Fig. 3 shows a detail of a latching arrangement for maintaining the cover in engagement with the housing, illustrating the elements in the unlatched position; Fig. 4 is a view similar to Fig. 3 illustrating the elements in a latched position; Fig. 5 is a longitudinal sectional elevation view of the vacuum cleaner; Fig. 6 is an enlarged sectional plan view partly broken away taken along the line 6—6 of Fig. 5; Fig. 7 is a sectional elevation view taken along the line 7—7 of Fig. 6; Fig. 8 is a sectional plan view showing a detail of the latching arrangement; Fig. 9 is a sectional elevation view taken along the line 9—9 of Fig. 5; Fig. 10 is an exploded perspective view showing details of the construction illustrated in Fig. 9; Fig. 11 is a sectional plan view taken along the line 11—11 of Fig. 5; and Fig. 12 is a sectional elevation view partly broken away taken along the line 12—12 of Fig. 5.

Referring now to Fig. 1, the vacuum cleaner includes a housing or casing 1 for enclosing the various operating elements. A portion of the top of the housing 1 is provided with a cover 2 for

providing access to the space within the housing. The cover is provided with a handle 3 for operating a latching mechanism to maintain the cover removably in sealing engagement with the housing. The non-removable portion of the top of the housing is provided with a handle 4 for carrying the cleaner. The cover is provided with an opening 5 at one end through which air is drawn into the housing, and a similar opening 6, shown more clearly in Fig. 5, is provided at the opposite end of the housing for the discharge of the air. Each of these openings is arranged to receive a suitable hose so that air may be either drawn inwardly through the hose or discharged therefrom. A button 7 projects from the top of the housing and is connected within the housing to a suitable switch for controlling the operation of the cleaner.

Referring now to Fig. 2 it can be seen that the 20 housing of the vacuum cleaner is divided into two compartments 8 and 9, the former being arranged for enclosing a suitable motor and fan for impelling the air and the latter enclosing a cord reel and a dust-collecting filter or bag 10. The bag 10 is assembled within the compartment 9 in reentrant form. The mouth of the bag is provided with a sealing gasket 11, formed of rubber or other similar material, with which the cover is designed to engage to provide a dust-tight seal. A frame 12 is provided within the compartment for supporting the lower or reentrant portion of the bag. This frame includes a plurality of generally vertically disposed wires 13 which are connected at their upper ends of a flat ring 14.

Two keepers 15 are secured to the housing at diametrically opposed positions adjacent the sealing gasket 11. These keepers are arranged for engagement by a latching mechanism associated with the cover for maintaining the cover in dust-sealing engagement with the gasket 11. The interior of the cover 2 includes a central dome-like portion 16 and a surrounding flat portion 17. The portion 17 is provided with two openings 18, only one of which is shown in this figure, through which the keepers 15 project when the cover is in its assembled position on the housing. In order to provide for latching engagement with the keepers the cover includes oppositely extending latching arms 19, only one of which is shown in this figure. A roller 20 is provided on the end of the arm 19 for facilitating engagement and disengagement with the keeper 15. To facilitate the guiding of the arm between the latched and unlatched positions two addi-

tional rollers 21 and 22 are provided on the arm 19. If desired, the roller 21 may be made integral with the roller 20. A guide 23 is secured to the portion 17 of the cover and includes an upstanding rib 24 which provides a track for the movement of the roller 21. This roller includes a groove 25 for facilitating cooperation between the track and the roller. In order to provide a further guide for the movement of the arm between the latched and the unlatched position and to limit the freedom of movement of the end of the arm 19 a channel 26 is secured to the dome-like portion 16 of the cover. The roller 22 is located within the channel 26 and moves along this channel during movement of the mechanism between the latched and the unlatched positions. It will be understood that similar rollers and guards are provided on the oppositely extending arm 19, not shown in this figure. The handle is connected, in a manner to be described in detail later, to the arms 19 so that movement of the handle between the position shown in Fig. 1 and the position shown in Fig. 2 results in shifting the arms from the latched position to the unlatched position.

Referring now to Figs. 3 and 4, the keepers 15 include a cam surface 27 for engagement by the roller 20. The end of the rib 24 adjacent the keeper 15 is tapered as indicated at 28 to facilitate entry of the roller 20 beneath the cam surface 27 of the keeper. The cam surface 27 includes an arcuate portion 29 for engagement with the correspondingly curved surface of the roller 20. In movement to the latched position the roller 20 is forced beneath the low point 30 of the cam surface and ultimately comes into engagement with the curved portion 29 in its latched position. The arm 19 is pressed downwardly as the roller passes beneath the low point 30 and the tendency of the arm 19 to return to its original shape brings the roller upwardly into engagement with the surface 29, as shown in the last position illustrated in Fig. 4, so that accidental return movement of the arm is prevented.

Referring now to Fig. 5, it can be seen that the fan compartment 8 and the dust-collecting compartment 9 are separated by a perforated partition 31, which acts as a bracing member for the walls of the casing 1. A motor 32 and a fan or impeller 33 are mounted within the compartment 8 for rotation about a vertical axis. To minimize the transmission of vibration from the motor and fan to the casing and hence to minimize noise resulting from the vibration of the walls of the casing, the motor and fan assembly is resiliently supported within the compartment 8 on a ring 34 of rubber or other vibration-absorbing material. Under the influence of the rotating fan air is drawn into the housing through the opening 5 in the cover, passes through the housing in the direction of the arrows, and is ultimately discharged through an enlarged passage on muffler 34a and the opening 6 at the opposite end of the housing. All of the air is directed through the dust-collecting bag or filter 10 so as to remove any dust particles therefrom prior to passage of the air into the fan compartment and its discharge through the opening 6. The cover is illustrated in this figure in its latched position wherein the portion 11 of the cover is forced into sealing engagement with the sealing gasket 11 of the dust-collecting bag 10. In its assembled position the dust-collecting bag 10 extends downwardly from its mouth, which is associated with the gasket 11, to the

bottom of the casing and then upwardly about the frame 12. During the passage of the air through the casing dust collects in the space between a downwardly extending portion 35 of the bag and an upwardly extending or reentrant portion 36. A circular frame 37 including an upper ring 38, a lower ring 39 and a plurality of connecting rods 40 is provided for the bag in order to assist in positioning the portions 35 and 36.

A reel 41, upon which the electric cord 42 for supplying power to the vacuum cleaner is wound, is located within the dust-collecting compartment 9. The reel 41 is arranged for rotating about a horizontal axis and is substantially enclosed within a dust-tight cover 43, which is secured to the housing 1. The cover 43 extends about the top and sides of the reel so as to prevent the bag 10 coming into contact with the reel. The frame 12 for supporting the portion 36 of the bag is secured to the cover 43, the lower end of the wires 13 being welded or otherwise suitably secured to the cover 43.

The cord 42 extends from the reel through a passage 44 within the housing and through an opening 45 to the exterior of the housing. The end of the cord is provided with a suitable plug 46 for connection to a power supplying outlet. The exterior of the housing is shaped, as indicated at 47, to provide a recess for the reception of the plug 46.

The reel 41 is provided with a spiral spring 48 which normally biases the reel for rotation in a counterclockwise direction as viewed in Fig. 5 so as to wind the cord 42 on the reel. Any desired length of the cord 42 may be withdrawn from the housing by grasping the exposed portion of the cord or plug and manually withdrawing the cord against the spring bias of the reel. To guide the cord during its withdrawal from the housing or its return to the housing a guide 49 is provided in the compartment 9 within the confines of the reel cover 43. This guide includes a shaft 50 and a roller 51 mounted thereon for facilitating the movement of the cord past the guide. In order to retain the cord in any desired withdrawing position the guide 49 includes an inclined face 52, and a stop 53 is provided for movement between a generally vertical position, as shown in solid lines in Fig. 5, and an inclined position adjacent the face 52, as shown by the dotted lines in Fig. 5. The stop 53 includes an opening 54 whose diameter is just slightly greater than the diameter of the cord 42. When the cord is being withdrawn from the housing the stop 53 occupies the solid line position shown in Fig. 5. In this position the stop is located in a plane perpendicular to the axis of the cord and the cord, therefore, passes freely through the opening 54. However, when the cord is moved in the opposite direction, that is, to the right as shown in Fig. 5, under the spring-biasing influence of the reel 41, the stop is moved to the right against the inclined face 52 and is forced to assume the inclined position shown by the dotted lines. In this position the plane of the stop is inclined to the axis of the cord and, since the diameter of the opening 54 is only slightly larger than the diameter of the cord, the cord binds against the edges of the opening 54, and further retraction under the influence of the spring-biased reel is prevented. Thus the user is enabled to withdraw the cord to any desired length depending on the distance the cleaner is located from the power outlet and, when the cord is released by the user it is auto-

matically locked in position, preventing any tendency of the reel to pull the plug from the power outlet.

In order to permit the winding of the cord on the reel when desired, a release cord or rope 55, which extends through the passage 44 to the exterior of the housing, is provided. One end of the rope is connected to the stop 53, as shown more clearly in Fig. 10, and the other end is connected to a suitable ring or eye 55a which is fastened to the exterior of the housing. When it is desired to allow the cord to be re-wound on the reel, the stop 53 is held in the solid line position by a pull exerted from the exterior of the housing on the accessible end of the rope, so that the cord may freely pass through the opening 54 to its wound position on the reel 41.

Details of the latching arrangement associated with the cover 2 are illustrated in Figs. 6, 7 and 8. The latch-operating handle 3 is mounted on a shaft 56 which extends vertically through an opening in the top of the cover 2. Two disks 57 and 58 are arranged in spaced relationship on the shaft 56. The arms 19 include a connecting central portion 59 which is clamped between the spaced disks 57 and 58. The clamping force is exerted by a plurality of screws 60 or other suitable fastening devices. In order to prevent any lateral shifting of the arms 19 a member 61, which is curved to fit the shape of the connecting portion 59 is located between the arms 19 and the clamping screws 60. The diameter of the member 61 is chosen so as to completely fill the space between the arms 19 and the clamping screws 60. In order to maintain the assembly in position during movement of the handle between latched and unlatched positions two plates 62 and 63 are provided on diametrically opposed sides of the disk 58. Each of the plates 62 and 63 includes an arcuate surface 64 adjacent the circumference of the disk 58, so as to provide an engaging surface for the disk during its turning movement. The plates 62 and 63 are held in place by screws 65 or other suitable fastening devices. The screws 65 extend through a reinforcing plate 66 and into threaded engagement with the plates 62 and 63. In order to transmit the motion of the latch-operating handle to the plate assembly 57, 58 and to the arms 19, the handle includes a depending portion 67 having a flange 68 of square cross-section at its lower end. The flange 68 fits within a recess 69 formed within the top of the disk 57. Thus movement of the handle is transmitted through the flange 68 to the disk 57 and thence to the arms 19 to effect operation of the latch. The handle 3 is secured to the shaft 56 by a pin 70, and the lower end of the shaft assembly is completed by a screw 71 which extends upwardly from the bottom of the plate 66 into engagement with the shaft 56. The lower end of the shaft 56 has a reduced diameter providing a shoulder 71a. This shoulder fits against the plate 66 to assist in providing an air seal.

The cover 2 includes a vertical section 72 which provides a stop for limiting the movement of the mechanism in the latched position, as best shown in Fig. 8. The roller 21 comes in contact with the stop 72 and further movement of the arms 19 in a clockwise direction is prevented. Thus when the handle is moved to the latching position movement of the arms 19 beyond the position shown in Fig. 4 is prevented

by engagement of the roller 21 with the stop 72, and accidental return movement to the unlatched position is prevented by reason of the cam surface 27 of the keeper 15, as previously described.

Details of the cord reel and its related elements are shown in Figs. 9 and 10. The cord reel 41 includes two disks 73 and 74 between which the cord is wound. The disk 74 includes a central cup-shaped portion 75 which provided a receptacle for a block 76 of insulating material. The reel structure further includes a cup-shaped member 77 which is welded or otherwise secured to the portion 75 of the disk 74. The member 77 includes a plurality of ears 78 which extend through slots provided in the disk 74 and are bent over to hold the disk 73 and the members 77 in engagement.

A shaft structure is mounted between the two sides of the cover 43 for supporting the reel. This shaft structure includes a plate 79 on the exterior of the cover 43 and a cooperating plate 80 on the interior of the cover, the two plates being clamped together against the cover by screws 81 or other suitable clamping devices. The plate 80 is provided with two inwardly extending lugs 82 and 83 which engage corresponding slots 84 in a sleeve 85, only one of the slots being shown in these figures. The sleeve 85 is supported at one end on a shouldered cylinder 86 which extends within the sleeve and into screw-threaded engagement with a second cylinder 87 within the sleeve 85. The shaft assembly is completed by a screw 88 extending from the exterior of the cover 43 into screw-threaded engagement with the shouldered cylinder 86. The plates 79 and 80 are clamped against a side wall of the cover 43 to provide an air seal for excluding air passing through the cleaner from the space occupied by the reel 41. A similar air seal is provided by the screw 88 in engagement with the other side wall of the cover 43.

In order to provide a bias for the reel tending to move the cord toward its second position a spiral spring 48 is arranged between the disk 73 and a wall of the cup-shaped member 77. One end of the spiral spring fits within a longitudinal slot 89 in the sleeve 85. The other end of the spring is secured to a transverse wall of the cup-shaped member 77 by a rivet 90 or other suitable fastening device. In order to provide for the rotation of the reel about the fixed sleeve 85 a collar 91 is arranged on a reduced section 92 of the sleeve. The collar 91 includes a slot 93 which in the assembled position is aligned with the slot 89 of the sleeve, and the end of the spring 48 extends into both the slot 93 and the slot 89. The collar 91 includes a bearing surface 94 upon which the disk 73 of the reel 41 revolves. The portion of the cup-shaped member 77 adjacent the shaft structure is clamped between two cooperating screw-threaded collars 95 and 96. The inner collar 95 is arranged to rotate on a reduced section 97 of the sleeve 85.

The insulating block 76 is provided with two concentric current-conducting rings 98 and 99 embedded therein. One of the current conducting wires 100 of the cord 42 is connected to the ring 98 and the other wire is connected to the ring 99. A stationary block 101 of electrical insulating material is arranged within the cover 43 adjacent the concentric rings 98 and 99. A pair of contacts 102 and 103 are mounted on

the block 101, the former for engagement with the ring 98 and the latter for engagement with the ring 99. Each of the contacts 102 and 103 is mounted on a strip 104 of resilient material, shown more clearly in Fig. 5. The resilient material presses each of the contacts firmly into engagement with its corresponding current-conducting ring. As shown more clearly in Fig. 5, a wire 105 is secured to the contact 102 and a second wire 106 is secured to the contact 103. The wires 105 and 106 extend through the casing to the motor 32 for supplying power to the motor. The provision of the concentric current-conducting rings 98 and 99 permits the supplying of power from the cord 42 to the motor regardless of the position of the cord reel 41.

The guide 49 for the cord 42 is illustrated in the bottom of the area enclosed by the cover 43 below the cord reel. Also illustrated is the stop 53 and the arrangement for securing the rope 55 to the stop. In order to provide for access to the cord reel when necessary the cover 43 is open at the bottom, and a closure member or plate 107 is provided to close this opening. In order to retain the closure member in position two recesses 108 and 109 are provided in opposite sides of the cover 43 and a U-shaped clamp 110, which is secured to the inner side of the closure plate 107, is arranged to engage the recesses 108 and 109. The U-shaped clamp 110 includes two resilient arms 111 and 112, each of the arms being provided with a portion 113, which is resiliently pressed into its respective recess when the closure plate is in position. Two supporting blocks 114 are welded or otherwise secured to the closure plate 107. The clamp 110 is secured to the supporting blocks by screws 115 or other suitable fastening devices. In order to assist in positioning the closure plate 107 within the bottom opening in the cover 43 an upwardly projecting lug 116 is provided near each corner of the closure plate. These lugs are of generally L-shape, one leg of the L being secured to the closure plate 107 and the other leg extending upwardly into the housing to accurately position the closure plate within the opening.

The tension on the spring 48 may be set or adjusted by inserting an open end wrench into engagement with the flat sides of the plate 80 after first removing the closure plate 107. The screws 81 are then removed and the plate 80 is turned to secure the proper tension on the spring 48. If it is necessary to shift the wrench for additional turning of the plate 80 a pin may be inserted temporarily through aligned holes in the members 79 and 80 to prevent unwinding of the spring. When the tension has been properly set the screws 81 are inserted and the closure plate 107 is again placed in position.

Another view of the cord 42 and its associated guide and stop elements is shown in Fig. 11. It can be seen that the cord extends through the passage 44 provided in the bottom of the housing, and the rope 55 for moving the stop 53 to its cord-releasing position also extends through the passage 44. In the vertical or cord-releasing position illustrated in Fig. 11 the stop 53 is held against two of the lugs 116. As shown in this figure, the guide 49 is secured to the supporting blocks 116 by screws 117 or other suitable fastening devices.

Referring now to Fig. 12 it can be seen that the wall stiffening partition 31 between the fan compartment and the dust-collecting compart-

ment is provided with a plurality of perforations 118 for the passage of air between the two compartments. The passage 44 in the lower portion of the housing is divided by a longitudinally extending bracket 119 which divides the passage 44 to provide individual conduits for the cord 42 and the rope 55.

While I have illustrated a specific embodiment of my invention, I do not desire my invention to be limited to the particular construction shown and described and I intend by the appended claims to cover all modifications in the spirit and scope of my invention.

What I claim as new and desire to secure by Letters Patent of the United States is:

1. A vacuum cleaner of the tank type comprising a housing including two compartments, a perforated partition between said compartments, a cord reel in one of said compartments, a frame positioned adjacent said cord reel and spaced therefrom, a dust-collecting bag in said one of said compartments, said bag including one portion adjacent said partition and a reentrant portion disposed about said frame, a fan and an electric driving motor therefor in the other of said compartments and electrical connections from said cord reel to said motor.

2. A vacuum cleaner of the tank type comprising a housing having an opening at each end, an electric motor mounted within one end of said housing for rotation about a vertical axis, an impeller driven by said motor and mounted within said housing coaxially with the motor for rotation about a vertical axis, a filter of inverted reentrant bag form arranged within the other end of said housing, means for directing air moved through said housing by said impeller between the openings through said filter to remove dust therefrom, an electric cord for supplying power to said motor, electrical connections from said cord to said motor, and a reel for said cord arranged within said housing under the inverted bag filter for rotation about a horizontal axis.

3. A vacuum cleaner of the tank type comprising a housing having an opening at each end, said housing including two transversely arranged compartments, an impeller for moving air between the openings and an electric driving motor therefor mounted in one of said compartments, a cord reel mounted in the other of said compartments, electrical connections to said motor from said cord reel, and a dust collecting bag in said other compartment positioned about said reel.

4. A vacuum cleaner of the tank type comprising a housing, said housing including a first and a second compartment, an impeller and an electric driving motor therefor mounted in said first compartment, a cord reel mounted in said second compartment, electrical connections to said motor from said reel, a dust collecting bag in said second compartment positioned about said reel, a removable cover for said second compartment for providing access to said bag, and a closure member for said second compartment for providing access to said reel.

5. A vacuum cleaner of the tank type comprising a housing including a fan compartment and a dust collecting compartment, a perforated partition between said compartments, a fan and an electric driving motor therefor in said fan compartment, a cord reel in said dust collecting compartment, electrical connections to said motor from said reel, a frame in said dust collecting compartment positioned around said cord

reel, and a dust collecting bag in said dust collecting compartment having a portion supported by said frame.
